FLOATING DRY DOCKS

Christopher J. Foster, 44 Whitehall St., Sands Point, N.Y.

Filed Mar. 14, 1957, Ser. No. 645,937

7 Claims. (Cl. 114—46)

My invention relates to an improvement in floating dry-docks and has for its object to provide a self-docking floating drydock of great economy of structure. The invention relates especially to the Rennie type of floating drydock having continuous steel wings spanning a series of detachable pontoons, one of which may readily be docked on the rest thereof.

It is established by the prior art that the introduction of a central air space or buoyancy chamber into a dry-dock having a rectangular pontoon body is an expensive luxury, as the bulkheads therefor and bracing of the chamber materially add to the weight of the dock center. Ordinarily in a pontoon of rectangular cross-section having such a chamber, no benefit by way of reducing the size or strength of the parts can be obtained by decreasing the transverse stresses encountered at the time the wings are first pumped out; because the transverse bending moments with the ship raised, control the design of the conventional dock, and the addition of a heavy central buoyancy chamber will materially increase the transverse bending moments with the ship raised. Now, however, I have discovered that in a Rennie type of dock, where the continuous steel wings are provided with heavy continuous bottoms, the weight of the wings, wing seats and fastenings oppose the ship moment to such a degree that the combined transverse stresses at the time the wings are first pumped out with the pontoons still full are the controlling factors; and I have also discovered that the use of a central buoyancy chamber within rectangular pontoons further reduces the controlling stresses in such a dock when the wings are first pumped out. This effect is produced in two ways: The additional buoyancy causes the dock to float higher and thereby reduces the water pressure on the outside of the dock, and the buoyancy chamber provides a substantial central lift instead of having a central ship load supported only by the buoyancy at the sides of the dock. As the controlling factors in the conventional Rennie dock with rectangular pontoons are the combined transverse stresses when the wings are first pumped out, a considerable economy of structure is achieved by the introduction of a center buoyancy chamber in this type of dock. Further, the detachable pontoon is rendered laterally stable by the buoyancy chamber, and no heavy longitudinal bulkheads are required for lateral stability in my preferred pontoon, which also for all practical purposes is rendered unsinkable when separated from the dock. In my pontoon construction for a very wide dock, where swash bulkheads are required to prevent a sudden shift of water just when the ship has been lifted clear out of the water and the metacentric height of ship and dock is suddenly reduced to a minimum, I prefer to install a shallow swash bulkhead, just high enough to cut or top the inside water plane while the ship bottom is still submerged. This shallow swash bulkhead is supplied with check valves such as shown in my copending application Serial No. 633,283, permitting the water to drain towards the pumps that are located at the sides of the dock;

2

towards which I prefer to slope the pontoon bottom. The ensuing parallelogrammic section of the pontoon insures a substantial freeboard at the center of the pontoon while it cuts the bilge water left in the pontoon into half of that of the conventional dock. Due to the combination of square pontoon ends, which lie at the sides of the completed dock, lower than the center of the dock with a center buoyancy chamber, and the required wing width as well as the dock width substantially reduced, my preferred self docking floating drydock weighs only 25% of its lifting capacity, which is an economy of structure never before achieved. As my invention comprises a new combination of old elements from which new and useful results flow, I do not claim only the combination of continuous sidewalls and detachable parallelogrammic pontoons with center buoyancy chambers as my invention, but I also claim as a method the several steps necessary to achieve said novel and useful results.

20 In the drawing—

Fig. I is a longitudinal elevation showing the center pontoon docked on the remaining two pontoons. Fig. II is a cross-section of my preferred drydock construction. Fig. III is a horizontal section through the pontoon taken at a level above the partial swash bulkheads.

Referring to the drawing where like reference characters designate corresponding parts, 1 denotes a floating drydock comprising two continuous wings 2, spanning a series of three pontoons 3. A relatively shallow buoyant air chamber 18, formed by the watertight bulkheads 10, divides each pontoon into two pumping compartments or chambers 17, which chambers communicate with the wing compartments 19, through the communication openings 21, that are cut through the wing bottoms 14. A deck 5 near the tops of each wing partitions off a safety hold 20, the buoyancy of which will prevent an accidental sinking of the dock. The center pontoon 3, in Fig. I is shown docked when raised on special blocking 7, while the ship 8 shown in Fig. II is docked when raised on the regular blocking 9. For longitudinal stability of the dock, the continuous wings, which I, for economy reasons prefer to make rectangular in cross section are partitioned off by bulkheads 6, that end at the safety deck 5. The pontoons are shown fastened to the continuous wings by the bolts 15, and the two pumping compartments of the pontoon are divided at their bottoms by shallow swash bulkheads 11, that are provided with the swing check valves 12, which open only towards the sides 3 of the dock and close towards the central chamber 18; so that if the dock should careen or heel, the flow of water from the high side of the dock through the bulkhead on that side towards the low side of the dock is prevented; this is reflected in a considerable saving in the wing thickness, without a reduction in the stability of the loaded dock. The end pontoons are provided with outriggers 4, which can be swung back over the pontoon deck for self docking, and the buoyancy chamber is provided with a shallow watertight bulkhead 13, that makes it possible to ballast the end pontoons properly against the eccentric loading of the outriggers when self docked. Attention is called to the fact that the outside water line 16 is substantially higher than the ship bottom when the ship in the dock is still substantially submerged, so that the stabilizing effect of the ship's waterplane is still in effect when the partial swash bulkhead 11 cuts the free waterline 16' in half, thus adding to the stability of the dock and ship, when they pass through the critical zone, where the water planes of the wings alone stabilize the dock.

Figures II and III indicate that the width of the buoyancy chamber does not exceed one-fifth of the entire width of the dock and that each pumping chamber 17

beside the buoyancy chamber is twice as large, having twice the width of the central chamber. Hence the lifting capacity of the dock is four times its weight, and the weight of the dock, due to the buoyancy of the chamber 18, is only 25% of the lifting capacity thereof.

It is to be noted that portions 22 of the bottom of the chambers 17 slope downward from the central chamber 18 towards the sides of the dock, beneath the wings 2; and portions of the deck 23 slope downward from the central chamber 18 towards the wings; and these sloping portions 23 of the deck are substantially parallel to the sloping portions 22 of the bottom. Hence, when the dock has been sunk and the ship is in place between the wings, and the dock is pumped out so that the ship rises, and the level of the water in the chambers 17 sinks towards portions 22 of the bottom, the water in the chambers 17 tends to flow downward and sideways towards the spaces under the walls, and concentrate in such spaces. The advantage of the buoyancy chamber is therefore greatest, and the water in the chambers 17 is largest in volume and heaviest adjacent the sides under the walls 2, and has a very marked balancing effect on the dock and the load of the ship; and immensely increases the stability of the dock as the ship is lifted entirely out of the water and the deck of the dock is entirely above the level thereof.

Figures II and III indicate that the shortest dimension of each pontoon extends along the sides of the dock when the pontoon is in position, and the longest dimension extends transversely of the dock. I prefer to call the longest dimensions of the pontoons the sides thereof, because the pontoons are disposed side by side when assembled; and the shorter dimensions may therefore be regarded as the ends of each pontoon; although these ends extend along the sides of the completed dock.

From this it follows that the buoyancy of the central chamber is larger than the submerged weight of the pontoon, but smaller than the combined weight of the pontoon and the weight of the wing portions superposed thereon; that is, the central buoyancy chamber will support the pontoon afloat even when it is filled with water, but the dock will sink when the pontoon and wings are both filled.

I do not wish to be understood to limit my claims to the shown structure as it is evident that alterations and modifications may be made in the adaptation of my invention without departing from the scope and spirit thereof.

I claim:

1. In a self-docking floating dry dock, a row of pontoons arranged side by side longitudinally of the dock, continuous wing walls supported on the ends of said pontoons, said ends being directly under said walls, detachable means for securing the pontoons to the walls, each pontoon having a relatively shallow central buoyancy chamber, the spaces between the said buoyancy chamber and the ends of said pontoons at the sides of the dock forming pumping chambers, said walls being in communication with said pumping chambers at the ends of each pontoon, the central chamber being such size that the buoyancy effect thereof is greater than the submerged weight of the pontoon but smaller than the submerged weight of the pontoon and the portions of the wings superimposed thereon, the dock having a deck which slopes downward at both sides of the central chamber, the bottom of the dock being parallel to the deck.

2. In a self-docking floating dry dock, a row of pontoons arranged side by side longitudinally of the dock, continuous wing walls supported on the ends of said pontoons, said ends being directly under said walls, detachable means for securing the pontoons to the walls, each pontoon having a relatively shallow central buoyancy chamber, the spaces between the said buoyancy chamber and the ends of said pontoons at the sides of the

dock forming pumping chambers, said walls being in communication with said pumping chambers at the ends of each pontoon, the central chamber being such size that the buoyancy effect thereof is greater than the submerged weight of the pontoon but smaller than the submerged weight of the pontoon and the portions of the wings superimposed thereon, the bottom of each pontoon sloping downward from the sides of the central chamber towards the ends of the pontoon under the wing walls thereon and being lowest directly under said wing walls.

3. In a self-docking floating dry dock, a row of pontoons arranged side by side longitudinally of the dock, continuous wing walls supported on the ends of said pontoons, said ends being directly under said walls, detachable means for securing the pontoons to the walls, each pontoon having a central buoyancy chamber, the spaces between the said buoyancy chamber and the ends of said pontoons at the sides of the dock forming pumping chambers, said walls being in communication with said pumping chambers at the ends of each pontoon, the central chamber being such size that the buoyancy effect thereof is greater than the submerged weight of the pontoon but smaller than the submerged weight of the pontoon and the portions of the wings superimposed thereon, the bottom of each pontoon sloping downward from the sides of the central chamber towards the ends of the pontoon under the wing walls thereon and being lowest directly under said wing walls.

4. A self-docking dry dock comprising hollow wing walls and a row of separated hollow pontoons substantially rectangular in cross-section arranged side by side longitudinally of said dock, the ends of said pontoons being directly under said wing walls, each pontoon having a central buoyancy chamber and spaces forming pumping chambers between the buoyancy chamber and said walls, said pumping chambers being in communication with the interior of said walls, the bottom of said pumping chambers sloping downward towards the sides of the dock, and being lowest under said walls, said pumping chambers having swash bulkheads extending longitudinally of the dock along the sloping bottom, each bulkhead having one-way valves therein which open only towards the side of the dock.

5. A self-docking dry dock comprising hollow wing walls and a row of separated hollow pontoons substantially rectangular in cross-section arranged side by side longitudinally of said dock, the ends of said pontoons being directly under said wing walls, each pontoon having a central buoyancy chamber and spaces forming pumping chambers between the buoyancy chamber and said walls, said pumping chambers being in communication with the interior of said walls, the bottom of said pumping chambers sloping downward towards the sides of the dock, and being lowest under said walls, said pumping chambers having swash bulkheads on said sloping bottoms extending longitudinally of said dock, each bulkhead having one-way valves therein which open only towards the side of the dock.

6. A self-docking dry dock comprising hollow wing walls and a row of separated hollow pontoons substantially rectangular in cross-section arranged side by side longitudinally of said dock, the ends of said pontoons being directly under said wing walls, each pontoon having a central buoyancy chamber and spaces forming pumping chambers between the buoyancy chamber and said walls, said pumping chambers being in communication with the interior of said walls, the bottom of said pumping chambers sloping downward towards the sides of the dock, and being lowest under said walls, said

pumping chambers having swash bulkheads on said sloping bottoms extending longitudinally of said dock, each bulkhead having one-way valves therein which open only towards the side of the dock, the width of said buoyancy chamber being substantially one-fifth of the width of said dock, and the pumping chambers extending over the remainder of the width of the dock, so that the lifting capacity of the dock is greatly increased.

7. In a self-docking floating dry dock, a row of pontoons arranged side by side longitudinally of the dock, continuous wing walls supported on the ends of said pontoons, said ends being directly under said walls, detachable means for securing the pontoons to the walls, each pontoon having a central buoyancy chamber, the spaces between said buoyancy chamber and the ends of said pontoons at the sides of the dock forming pumping chambers, low bulkheads in each pumping chamber extending longitudinally of the dock, each bulkhead having valves opening only towards the sides, the pontoons having substantially constant depth from end to end, said walls being in communication with said pumping chambers at

the ends of each pontoon, the central chamber being of such size that the buoyancy effect thereof is greater than the submerged weight of the pontoon, but smaller than the submerged weight of the pontoon and the portions 5 of the wings superimposed thereon.
